CLAIM

The ornamental design for a car seat as shown and described.

DESCRIPTION

FIG. 1 is a perspective view of the car seat showing our new design in a first embodiment; FIG. 2 is a front elevational view of the car seat thereof; FIG. 3 is a rear elevational view of the car seat thereof; FIG. 4 is a left side elevational view of the car seat thereof; FIG. 5 is a right side elevational view of the car seat thereof; FIG. 6 is a top plan view of the car seat thereof; and, FIG. 7 is a bottom plan view of the car seat thereof.

(Continued)

The dashed broken lines depict portions of the car seat that form no part of the claimed design.
